CLAIM

The ornamental design for a decorative panel, as shown and described.

DESCRIPTION

FIG. 1 is a perspective view of a decorative panel.

FIG. 2 is a front elevation view thereof.

FIG. 3 is a rear elevation view thereof.

FIG. 4 is a right side elevation view thereof. A left side elevation view is a mirror image of the right side elevation view.

FIG. 5 is a top plan view thereof.

FIG. 6 is a bottom plan view thereof.

FIG. 7 is a cross-sectional view taken along the line 7-7 in FIG. 5; and,

FIG. 8 is a referential perspective view showing use thereof. The broken lines in FIG. 8 depict unclaimed environment and form no part of the claimed design.
